UNITED STATES PATENT OFFICE.

OTTO M. BERGMAN, OF ROCHESTER, NEW YORK.

FLYING MACHINE.

Application filed January 2, 1925. Serial No. 67.

My invention relates to improvements in flying machines and has for its object to provide improved propelling means for machines of this kind.

5 A further object of the invention is to provide an improved propelling mechanism embodying a system of relatively small propellers designed to increase the thrusting power of the machine and at the same time 10 permitting it to be driven by a relatively small or low speed motor.

Another object of the invention is to provide a system of relatively small propellers mounted to travel upon a circular track 15 about the axis of the main drive shaft of the engine and to be advanced upon the track by suitable means operated by the shaft and at the same time being made to rotate about their own axes for the purpose of propelling 20 the machine in the direction desired.

To these and other ends the invention resides in certain improvements and combinations of parts all as will hereinafter be more fully described, the novel features being 25 pointed out in the claims at the end of the specification.

In the drawings:

Figure 1 is a front elevational view illustrating one embodiment of the invention, 30 and.

Figure 2 is a top plan view of the same.

Similar reference numerals throughout the several views indicate the same parts.

The principles of the present invention 35 may be employed in connection with different types of flying machines, but are particularly adapted for use with heavier than air machines.

In the present embodiment of the invention I have shown an engine or motor 10 having a drive shaft 11 carrying a cross arm 12 which may be in the form of a propeller as shown, or constructed in any desired manner to best afford a suitable driving means 40 for a series of relatively small propellers 13 mounted and operated in a manner herein-after pointed out.

The propellers 13 are each provided with an arbor or spindle 14 with which is rigidly connected a pair of rollers preferably in the form of grooved pulleys 15 and 16, adapted to travel about the axis of the drive shaft 11 upon stationary wheel shaped frames having circular tracks 17 and 18 which are preferably beveled to correspond to the bevel of the pulleys as shown in Figure 1. The

tracks or propeller guides are preferably supported by a series of spokes 19 radiating from the front and rear hubs 20 and 21 through which the drive shaft 11 is extended, said hubs being suitably secured to the engine as by means of a frame member 22 shown in Figure 2. The spokes are well adapted to support the tracks or guides for the propellers and afford but little resistance 60 to the air during advancement of the machine.

The spindles 14, between the pulleys 15 and 16, are each provided with a loosely mounted sleeve or bearing 23 as shown in 70 Figure 2. A pair of cables 24 and 25 are each extended around and between the circular tracks 17 and 18 and are connected with the sleeves 23, preferably by means of suitable clamping members as indicated at 26. 75

The ends of the cables 24 and 25 are suitably connected with the cross arm 12, as by means of the brackets 27, which are bolted or otherwise secured to said cross arm. The cross arm forms a driving member for ad- 80

vancing the bearings 23 and they in turn cause the pulleys to roll upon their respective tracks, thus causing the propellers 13 to roll also since the latter are rigidly connected with the pulleys. Thus, the propellers 85 are frictionally driven and have a rotational movement about their own axes, their speed being proportional to the speed of the driving member 12. However, for every revolution of the driving member each propeller 90 will travel the entire distance around the periphery of the circular frame. The rotational speed of each propeller will therefore be a number of times greater than the speed of the driving member 12 or that of the drive 95

shaft 11, depending upon the diameter of the tracks and the diameter of the pulleys travelling thereon. By reducing the diameter of the tracks and increasing the diameter of the pulleys the speed of the propellers may 100 be reduced without reducing the speed of the driving member 12. These proportions can of course be varied to effect an increase or decrease of the speed of the propellers for a given speed of the engine in order to obtain 105 the results desired. With the mechanism shown the motor may be driven at a relatively low speed though operating at the same time to drive the propellers at a relatively high speed in order to afford the necessary propelling power for the machine. Thus, the life of the motor may be increased 110

by reducing its speed and it can therefore be made lighter as well as safer and more economical to operate.

While the drawings illustrate the principles of the invention they are more or less diagrammatic in form and it will be understood that the several structures may be varied as desired within the scope of the claims to increase the efficiency and practicability of the propelling mechanism without departing from the spirit of the invention.

I claim as my invention:

1. In a flying machine, the combination with an engine and a frame including a pair of tracks, a propeller located at one side of the tracks and adapted to be driven by the engine, a series of relatively small propellers mounted laterally of the first mentioned propeller and each having a spindle and a pair of wheels adapted to roll upon said tracks, bearings between said wheels in which said spindles are free to rotate, and means operatively connecting the first mentioned propeller with the bearings.

2. In a flying machine, a frame having a circular track thereon, a series of rollers mounted to travel upon said track and held against lateral displacement thereby, propellers connected with said rollers to revolve therewith, and means for advancing the rollers upon the track.

3. In a flying machine, a frame having a circular track thereon, a series of rollers mounted to travel upon the track and held against lateral displacement thereby, propellers connected with said rollers to revolve therewith, means connecting the rollers one with another, and means for driving said roller connecting means.

4. In a flying machine, a frame having a circular track thereon, a series of rollers mounted to travel upon the outer periphery of the track, propellers connected with said rollers to revolve therewith, a cable connecting the rollers, and means for actuating the cable to cause the rollers to travel upon the track.

5. In a flying machine, a frame having spaced circular tracks thereon, a series of spaced propellers each provided with a spindle having grooved pulleys adapted to roll upon the track, bearings in which the spindle are adapted to rotate, and means for moving the bearings circumferentially of the track.

6. In a flying machine, a frame having spaced tracks thereon, a series of propellers each having flanged rollers connected therewith and adapted to travel upon and to be held against lateral displacement by the tracks and means for advancing the rollers upon the tracks.

7. In a flying machine, a frame having spaced tracks thereon, a series of propellers

each having a spindle provided with rollers adapted to travel upon said tracks, bearings for each of the spindles, means connecting the bearings one with another, and means located in advance of the tracks for actuating said last mentioned means to cause the rollers to travel upon said tracks.

8. In a flying machine, a frame having a circular track thereon, a series of spaced propellers mounted to travel circumferentially upon the outer periphery of said track and each being adapted at the same time to rotate about its own axis, and to be held against lateral displacement by the track, and means for advancing the propellers upon the track.

9. In a flying machine, the combination with an engine and a frame including circular tracks, of a propeller adapted to be rotated by the engine in advance of the tracks, a second propeller supported by said tracks for circumferential movement thereon, arms extending laterally from the first mentioned propeller and connecting means between the arms and the second mentioned propeller adapted to advance the latter.

10. In a flying machine, the combination with an engine and a frame having a circular track thereon, of a series of propellers mounted to travel upon said track and adapted to travel upon and to be held against lateral displacement thereby and each being adapted to rotate about its own axis while moving thereon, a main propeller driven by the engine in advance of said track and means extending rearwardly from said main propeller and adapted to advance the first mentioned propellers.

11. In a flying machine, the combination with an engine including a shaft driven thereby and having a cross arm thereon, a circular track mounted adjacent the engine, of a series of propellers mounted to roll upon the track and adapted to be supported independently of the cross arm, means carried by the cross arm adapted to revolve about the track and means operatively connecting the last mentioned means with said propellers to advance them upon the track.

12. In a flying machine, the combination with an engine including a shaft driven thereby and a circular track mounted adjacent the engine, of a series of propellers mounted to roll upon the track and adapted to be supported thereby, a propeller fixed upon said shaft in advance of the track and means including a flexible operating connection disposed between the main propeller and said series of propellers to advance the latter upon said track.

13. In a flying machine, the combination with an engine and a circular track mounted adjacent thereto, of a series of propellers provided with flanged rollers adapted to be rotated through frictional engagement with

the outer peripheral face of the track to effect rotation of the propellers and means driven by the engine adapted to advance the rollers upon the track.

5 14. In a flying machine, the combination with an engine and a frame including a track, a propeller disposed in advance of the track and adapted to be driven by the en-

gine, a series of relatively small propellers located rearwardly of said track and each 10 having a forwardly projecting support including a wheel adapted to roll upon the track, means connecting said supports and means operatively connecting the first mentioned propeller with said connecting means.

OTTO M. BERGMAN.
